UNITED STATES PATENT OFFICE.

WILLIAM DREUSIKE, OF TERRE HAUTE, INDIANA.

IMPROVEMENT IN REFRIGERATORS.

Specification forming part of Letters Patent No. **222,473**, dated December 9, 1879; application filed September 17, 1879.

To all whom it may concern:

Be it known that I, WILLIAM DREUSIKE, of Terre Haute, in the county of Vigo, and in the State of Indiana, have invented certain new and useful Improvements in Refrigerators and Refrigerating-Houses; and I do hereby declare that the following is a full, clear, and exact description thereof, reference being had to the accompanying drawings, and to the letters of reference marked thereon, making a part of this specification.

My invention relates to refrigerators and refrigerating-houses having an ice-room above and a cooling-room below separated by an ice-rack; and it consists in combining therewith a sectional ceiling under the ice-rack and the top ceiling, each section being hung upon a rod adjustably supported in an inclined position, and provided at its lower edge with a gutter; also, in the combination of the ceiling-section with gutter, hinging-rod, cord, pulley, and balancing-weight.

My invention further consists in the construction of the ceiling-section of double thickness with an interposed non-conductor, a top covering, gutter, and connecting-hooks; also, in the combination of the cooling-chamber, ice-chamber with interior walls, air-flue, solid ceiling, ice-rack, and adjustable sectional ceilings, all as will be hereinafter more fully set forth.

In the annexed drawings, Figure 1 is a vertical section of a refrigerating store-room embodying my invention. Figs. 2 and 3 are detail views of parts thereof.

C represents the walls of the house or building, made double and non-conducting in any suitable manner. The building is by an ice-rack, H, divided into an upper or ice room, A, and a lower or cooling room, B.

The ice-rack H is supported upon joists G, laid upon timbers E, which may be supported upon posts, or otherwise arranged, according to the structure of the building. Below the ice-rack H is a suspended ceiling to catch the drip from the ice above. This ceiling is made in sections I I, each section supported at its upper end by a rod, J, and having a gutter, K, formed along its lower edge to carry off the drip to the waste-pipe. Each section of the ceiling is held in an inclined position by

means of weights L and cords M, passing over pulleys N, suspended by straps or hooks O from the joists G.

The timbers E are protected from the drip by means of galvanized iron or other coverings P, interposed between said timbers and the joists G.

The ice-room A is provided with a ceiling, f, which is double and packed, or with paper between. Within the ice-room are interior double walls, d, forming a warm-air opening or flue, e, from the cooling room to near the top of the ice-room, letting the warm air enter the ice-room immediately below the ceiling f. c c are beveled slats in the inner walls, d, at the bottom.

The ice-room is also provided with sectional suspended ceiling I, hung upon rods J', provided with gutters K', and suspended by straps or rods b. The ceiling I' is immediately below the entrance at the top from the warm-air flue e, and is intended to catch the drip from condensation on the top ceiling, f, of the ice-room. In a large room the center of the sectional ceiling I' is intended to rest on the ice and lower with it as the ice melts, the opposite sides being supported by the rods J'.

In the construction of the sectional ceilings each section is composed of two thicknesses of tongue-and-grooved ceiling-boards, i i, with paper or other non-conductor j between them. The top is covered with roofing-felt, galvanized iron, or zinc, k, to carry off the drip emptying into the gutter K or K', which leads to the main discharge-pipe.

At the upper edge the ceiling-section is single, the under portion being cut away to extend beyond the supporting-rod J, and it has hooks g attached to it by screws to pass over said rod J.

Having thus fully described my invention, what I claim as new, and desire to secure by Letters Patent, is—

1. The combination, in a refrigerator or refrigerating-house, of an ice-room above, a cooling-room below, a separating ice-rack forming the division between the two, and sectional ceiling under the ice-rack and top ceiling, each section being hung at one edge on a rod and adjustably supported in an inclined

position, and provided along its lower edge with a gutter, substantially as and for the purposes herein set forth.

2. The combination of the rod J, ceiling-section I, with gutter K, cord M, pulley N, and weight L, substantially as and for the purposes herein set forth.

3. The ceiling-section composed of the double thicknesses *i i*, with non-conductor *j* between them, top covering, *k*, gutter K, and hooks *g*, substantially as shown and described.

4. The combination of the cooling-chamber

B, ice-chamber A, with interior walls, *d*, air-flue *e*, solid ceiling *f*, ice-rack *H*, and the adjustable sectional suspended ceilings I I', all constructed and arranged substantially as and for the purposes herein set forth.

In testimony that I claim the foregoing I have hereunto set my hand this 13th day of June, 1879.

WM. DREUSIKE.
